UNITED STATES PATENT OFFICE.

STEVEN B. TATULIS, OF CHICAGO, ILLINOIS.

FLOOR-WASHING MACHINE.

1,271,629.

Specification of Letters Patent.

Patented July 9, 1918.

Application filed September 27, 1917. Serial No. 193,423.

To all whom it may concern:

Be it known that I, STEVEN B. TATULIS, a subject of the King of Greece, and a resident of the city of Chicago, county of Cook, 5 and State of Illinois, have invented certain new and useful Improvements in Floor-Washing Machines, of which the following is a specification.

My invention relates to improvements in 10 floor washing machines and has for its object the production of a device of this character through the medium of which a floor may be washed with ease and expedition. A further object is the production of a device 15 as mentioned which will be of durable and economical construction and efficient in use.

Other objects will appear hereinafter.

The invention consists in the combinations 20 and arrangements of parts hereinafter described and claimed.

The invention will be best understood by reference to the accompanying drawings forming a part of this specification, and in which,

25 Figure 1 is a side elevation of a floor washing machine embodying the invention,

Fig. 2, a vertical, longitudinal section through the machine,

Fig. 3, a top plan view of the machine 30 with cover, handle and cleansing liquid reservoir removed, and,

Fig. 4, a section taken on line 4—4 of Fig. 1.

The preferred form of construction as 35 illustrated in the drawings comprises an elongated, rectangular carriage or housing 5, which is mounted for movement over the floor to be washed on wheels 6. Provided at the front end of carriage or housing 5 is a 40 rotary scrubbing brush 7, adapted for engagement with the floor. The brush 7 is driven through the medium of an endless sprocket chain 8 which passes around a sprocket wheel 9 connected with said brush.

45 Said sprocket chain is driven through the medium of an electric motor 10 mounted in the housing 5, the power shaft of said motor carrying a gear 11, which meshes with a gear 12 on a shaft 13, the latter carrying 50 a sprocket wheel 14, around which the chain 8 passes, as is clearly seen in Fig. 1.

Carried at the front end of the machine directly over the brush 7 is a cleansing liquid reservoir 15, the upper side of which is 55 provided with a hinged door 16, through

which the cleansing liquid may be readily introduced into said reservoir. The bottom of said reservoir, adjacent the front edge thereof, is provided with a plurality of spaced discharge openings 17, which are 60 controlled by a slidably mounted valve bar 18, having spaced perforations therein adapted for registration with the opening 17, as is clearly seen in Fig. 4. Sliding adjustment of said valve bar is effected by 65 means of a handle 19 provided at one end of said bar. The cleansing liquid thus discharged from the reservoir 15 is deposited on to the brush 7 whence the same is carried by the brush to and utilized in the 70 washing or scrubbing of the floor.

The cleansing liquid remaining on the floor after the passage of the scrubbing brush thereover is collected or absorbed by an endless apron mop 20, which passes 75 around a series of rollers 21, 22, 23, 24 and 25. The roller 21 is secured to shaft 13 whereby, in the operation of the motor 10, said mop will be rotated or moved longitudinally, as will be readily understood. 80 Coöoperating with roller 25 is a second roller 26, the mop, as the same passes between said rollers 25 and 26, being compressed to force the liquid which has been collected thereby, therefrom, and into a collecting receptacle 27. It will thus be seen, in the operation of the machine, that the floor will first be scrubbed by the brush 7, which will be moistened by the cleansing liquid deposited thereon from the reservoir 15. After 85 the floor has thus been scrubbed by the brush 7, any liquid remaining thereon will be immediately absorbed by the mop 20 and carried thereby for deposit into receptacle 27 upon passage of the mop between rollers 25 and 26. After the washing operation has been completed the receptacle 27 will be emptied. To assist in the driving of the mop 20, the roller 25 may be provided with 90 a sprocket wheel 28 for engagement with the sprocket chain 8.

Carried at each end of the device is a vertical movable squeegee 29, carried by arms 30 fulcrumed at 31 to the carriage or housing 5. The arms 30 are provided with teeth 105 32, which are adapted to mesh with gears 33 fixed to wheels 6. The arrangement is such that the squeegees 29 at opposite ends of the device are operatively connected through gears 33 with the wheels 6, the direction 110

of rotations of said wheels determining whether or not said squeegees are leveled or lowered, the arrangement being such that said squeegees will operate alternately so that when the device is moved forwardly the squeegee at the rearward end thereof will be moved downwardly into operative engagement with the floor, whereas the squeegee at the front end of the device will be elevated 10 into inoperative position. When the device is moved rearwardly, the reverse movement of said squeegees will be effected; that is, the squeegee at the front end of the machine will be lowered to operative position, whereas the squeegee at the rearward end of the device will be elevated into inoperative position. The squeegees will serve to gather or collect any moisture or liquid remaining on the floor after the passage of the mop there- 20 over, the moisture or liquid thus gathered or collected by either squeegee being in close proximity with the mop where the same will be absorbed and thus the floor rendered practically perfectly dry when the machine has 25 passed thereover.

Secured to the cover of the carriage or housing is a handle 34, whereby the device may be manually moved over the floor in the employment of the same.

While I have illustrated and described the preferred form of construction for carrying my invention into effect, this is capable of variations and modifications without departing from the spirit of the invention. I, therefore, do not wish to be limited 35 to the precise details of construction set forth, but desire to avail myself of such variations and modifications as come within the scope of the appended claims.

Having described my invention what I claim as new and desire to secure by Letters Patent is:

1. A floor washing machine comprising a wheeled carriage; a cleansing liquid reservoir supported by said carriage; a scrubbing element adapted for engagement with the floor; a cleansing liquid supply adapted to discharge cleansing liquid onto said scrubbing element; means for mopping up the floor to remove the cleansing liquid therefrom; a squeegee carried by said carriage at one end thereof adapted to engage with the floor to collect the liquid thereon for absorption by said mopping means; and means 45 for automatically moving said squeegee into and out of operative engagement with the floor in the movement of the carriage in op- 50 55

posite directions over the floor, substantially as described.

2. A floor washing machine comprising a wheeled carriage; a cleansing liquid reservoir supported by said carriage; a scrubbing element adapted for engagement with the floor; a cleansing liquid supply adapted to discharge cleansing liquid onto said scrubbing element; means for mopping up the floor to remove the cleansing liquid therefrom; a vertically movable squeegee carried by said carriage at each end thereof adapted to engage with the floor to collect the liquid thereon for absorption by said mopping means; and means, adapted upon movement of the device in one direction, to automatically raise the squeegee at one end of the carriage to inoperative position and to lower the other squeegee to operative position, and, upon movement of the device in the opposite direction to automatically reverse the movement of said squeegees, substantially as described.

3. A floor washing machine comprising a wheeled carriage; a cleansing liquid reservoir supported by said carriage; a scrubbing element adapted for engagement with the floor; a cleansing liquid supply adapted to discharge cleansing liquid onto said scrubbing element; means for mopping up the floor to remove the cleansing liquid therefrom; a vertically movable squeegee carried by said carriage at each end thereof adapted to engage with the floor to collect the liquid thereon for absorption by said mopping means; means, adapted upon movement of the device in one direction, to automatically raise the squeegee at one end of the carriage to inoperative position, and to lower the other squeegee to operative position, and, upon movement of the device in the opposite direction to automatically reverse the movement of said squeegees, said last mentioned means comprising a rockingly mounted holder for each squeegee; and a gear coöperating with said holder whereby upon forward and rearward movement of the device said holder will be rocked first in one direction and then in the other, substantially as described.

In testimony whereof I have signed my name to this specification in the presence of two subscribing witnesses.

STEVEN B. TATULIS.
